R. J. BURLEW.
WINDOW SASH FASTENER.
APPLICATION FILED NOV. 26, 1912.

1,056,003.

Patented Mar. 18, 1913.

COLUMBIA PLANOGRAPH CO., WASHINGTON, D. C.

UNITED STATES PATENT OFFICE.

RICHARD J. BURLEW, OF OLIVE BRANCH, OHIO.

WINDOW-SASH FASTENER.

1,056,003.

Specification of Letters Patent. Patented Mar. 18, 1913.

Application filed November 26, 1912. Serial No. 733,664.

To all whom it may concern:

Be it known that I, RICHARD J. BURLEW, a citizen of the United States, residing at Olive Branch, in the county of Clermont 5 and State of Ohio, have invented certain new and useful Improvements in Window-Sash Fasteners, of which the following is a specification.

My invention relates to improvements in 10 window sash fasteners.

One of its objects is to provide a strong and durable fastening to resist attempts to enter from the outside.

Another object is to provide a simple 15 fastening capable of being readily attached to any window at any time, and attached and operating upon novel principles.

Another object is to provide fastening means to hold the sashes in different relative 20 positions from closed to open, and to positively lock the fastening means to each sash.

Another object is to provide fastening means not readily tampered with from the exterior.

25 My invention also comprises certain details of form, combination and arrangement, all of which will be fully set forth in the description of the accompanying drawings, in which:

30 Figures 1 and 2 represent in plan view opposite halves of a window illustrating modified forms of my improved sash fastener. Fig. 3 is a vertical section on line *v v* of Fig. 1. Fig. 4 is a detail sectional view taken through the lower sash on line *z z* of Fig. 2. Fig. 5 is a perspective view of the locking bar illustrated in Figs. 2 and 4 detached. Fig. 6 is a perspective view of the locking bar illustrated in Figs.

40 1 and 3 detached. Fig. 7 is a detail sectional view illustrating a modification in which the locking bar is positively latched to the lower sash. Fig. 8 is a detail sectional view illustrating a modification. 45 The accompanying drawings illustrate the preferred embodiments of my invention.

As illustrated in Figs. 1, 3, and 6, A represents a window frame, B the upper sash, and D the lower sash, which is provided 50 with one or more recesses 2 in one of the stiles. A locking or fastening bar E substantially of the form illustrated in Fig. 6 is bent at the upper end and provided with a shoe 3 which is seated against the inner face of the upper sash and fastened thereto by screws. The bent upper portion 4 when

the sashes are closed seats against the facing strip 5 attached to the top or lintel of the window frame. The lower end 6 of the bar E is bent inwardly to engage and seat 60 in one of the recesses 2, or when the sashes are in full open position to engage beneath the lower edge of the lower sash. When the lower end of bar E is in engagement with the upper recesses 2 the two sashes are 65 locked together in the closed position, and any upward pressure on the lower sash is resisted both by the attachment of bar E to the upper sash and also by the engagement of part 4 of bar E against the window 70 frame.

When the sashes are counterweighted and the end 6 of bar E is engaged with one of the lower recesses 2 or under the lower edge of sash D, the two sashes are locked together 75 and may be moved up or down together to leave an open space either above or below. When the sashes are similarly locked together and are not counterweighted, an opening is left above the upper sash. In 80 order to move the end 6 from one position of adjustment to another, the bar E is sprung away from the lower sash by hand until the member 6 clears the recess 2 after which the sashes are adjusted to a new position and the 85 member 6 engaged in a new position.

In the modification Fig. 7, D' represents the stile of the lower sash in a recess in the inner face of which is seated a metal housing 10 which has a recess 2' to receive the inwardly bent lower end 6' of the fastening bar E', the upper end of which is similar to that illustrated in Fig. 6, and attached relative to the upper sash and window frame as illustrated in Figs. 1 and 3. A spring 95 actuated latch bar 11 is seated in the housing 10 in position for its forward end 12 to engage a notch 14 in the end of member 6' to positively lock the member 6' in the recess 2' to prevent the two sashes being accidentally disengaged or tampered with from the exterior. A knob 15 enables the latch bar 11 to be retracted when it is desired to release the member 6'.

In the modification Figs. 2, 4, and 5 the 105 fastening bar H is designed to lock the upper and lower sashes together only in the closed position. The bar H is attached to the upper sash B' and relative to the window frame substantially in the manner 110 heretofore described by means of a foot 16 secured by screws to the upper portion of

the upper sash. A recess 17 is formed in the upper end of one of the stiles of the lower sash K, and the lower end of the bar H is sprung inwardly slightly so as to 5 firmly seat in the recess 17 when the sashes are brought to closed position. When it is desired to open the window the lower end of bar H is sprung by hand out of the recess 17, and while the sashes are in open 10 position bears against the face of the stile of the lower sash.

In the modification Fig. 8, the fastening bar M is attached by a foot 20 to the upper portion of the lower sash, and its upper end 15 21 bent to engage the window frame when the sashes are closed, and its free end 22 is in position to engage any one of several recesses 24 in one of the stiles of the upper sash, being operated substantially as heretofore described.

The locking bar, in either modification, may be attached at either side of the window as desired, or at both sides if desired.

My improved mechanism as herein illustrated and described is capable of considerable modification without departing from the principle of my invention.

Having described my invention, what I claim is:

30 1. In combination with a window frame and upper and lower sashes, a fastener comprising a bar attached at one end to the upper portion of one sash and extending out of the path of travel of the lower sash to the upper portion of the opposite sash, said bar being bent at the upper end so as to engage the lintel of the window frame when the sashes are in closed position, the 35

free end of said bar being in position to engage a recess in the stile of one of said sashes to lock said sashes together in closed position.

2. In combination with a window frame, upper and lower sashes, the stile of one of said sashes being provided with a plurality of sockets, and a fastener comprising a bar attached at one end to the upper portion of one sash and extending out of the path of travel of the lower sash to the upper portion of the opposite sash, the free end of said bar being in position to selectively engage said respective sockets in the stile of one of said sashes to lock said sashes in different relative positions.

3. In combination with a window frame, an upper sash, and a lower sash provided with a plurality of recesses in the inner face of one of its stiles, a vertically disposed locking bar occupying a position out of the path of travel of the lower sash, bent at its upper end and rigidly attached at said upper bent end to the upper sash, said bent upper end being in position to engage the lintel of the window frame when the sashes are in closed position, the free lower end of said bar being in position to engage the respective recesses in the stile of said lower sash, and to be disengaged therefrom by hand to differently adjust said sashes.

60 In testimony whereof I have affixed my signature in presence of two witnesses.

RICHARD J. BURLEW.
